FIG. 5.

The diagram illustrates a mechanical assembly, likely a component of a typewriter. It features a long horizontal bar with a central circular hole. Numbered callouts point to specific parts: '28' and '30' point to the top edge of the bar; '29' and '31' point to the right edge; '36' points to a vertical support on the left; '37' points to a vertical support on the right; '81' points to a small rectangular part; '78' and '82' point to the bottom edge of the horizontal bar; '79' and '80' point to the left edge of the horizontal bar. The assembly appears to be a combination of a main frame and various internal and external supports.

INVALID BED WITH FLUID OPERATED SECTIONS

Norman H. Pardoe, Lusby, Md., assignor to
Albert J. MacDonald, Malden, Mass.Substituted for abandoned application Serial No.
498,105, August 10, 1943. This application Au-
gust 8, 1950, Serial No. 178,223

3 Claims. (Cl. 5—69)

1

This invention relates to beds and more particularly to invalid beds, having adjustable head and/or foot sections, and the application is a substitute for application Serial No. 498,105, filed August 10, 1943, and which was later forfeited and became abandoned.

An important object of the invention is to provide such a bed provided with means to permit the invalid to easily adjust either or both of the sections at will.

Another object is to provide means for adjustment of the sections to any number of temporarily fixed positions, and auxiliary means for preventing changes of the adjustment by the invalid. Thus, a nurse or attendant may make a suitable adjustment of the sections and then secure the adjustment against change thereof by the invalid.

Still another important object is to provide a hydraulically-operated, adjustable head and/or foot section invalid bed wherein the adjustment may be made without jars or jerks on the part of the section elevating and lowering means.

Yet another object is to provide a hydraulically-operated, adjustable head and/or foot section invalid bed, the operating means for the sections being compact and within easy reach without stooping.

Another object is to provide manipulating means for an adjustable head and/or foot section invalid bed, which means may be readily attached to either side of a bed.

Still another important object is to provide an invalid bed, wherein a doubly adjustable foot section is provided, since the foot section comprises two portions, pivoted together, so that there may be an angular adjustment of the two portions as well as an angular adjustment of the entire foot section with reference to any other section, or so that the foot section may be raised and the two portions thereof be in substantially the same plane.

Other objects and advantages of this invention will be apparent during the course of the following detailed description, taken in connection with the accompanying drawings, forming a part of this specification, and in which drawings—

Figure 1 is a side elevation of the novel bed with the head and foot sections lowered.

Figure 2 is a fragmentary top plan of the same, with operating mechanism partly bracket-supported thereby.

Figure 3 is a view, somewhat similar to Figure 1, but with portions of the operating means in vertical section, and the head and foot sections raised.

Figure 4 is a fragmentary portion of the novel bed, with the two portions of the foot section in substantially the same plane.

2

Figure 5 is a fragmentary portion of the bed, and with the two portions of the foot section in a position different from those of Figures 1 to 4 inclusive.

5 Figure 6 is a horizontal section substantially on the line 6—6 of Figure 3.

Figure 7 is a vertical section on substantially the line 7—7 of Figure 3.

10 Figure 8 is a vertical section thru a bracket adapted to be attached to the bed and the operating mechanism, shown in Figure 2.

Figure 9 is a vertical section thru a pivotal connection between the piston rod of the operating mechanism and movable sections of the novel bed.

15 Figure 10 is a fragmentary elevation, with two portions in section, of a supporting band for part of the operating mechanism.

Figure 11 is a pivotal connection between cylinders of the operating mechanism and the bed frame, also employed in the novel bed.

20 Figure 12 is a section thru a portion of a pump cylinder, and side elevations of check valves employed in the pump with their housings in section.

Figure 13 is a vertical section of a cylinder employed in the operating mechanism of the novel bed assembly.

25 In the drawings, wherein for the purpose of illustration is shown a preferred embodiment of the invention and wherein similar reference characters designate corresponding parts throughout the several views, the letter A may designate the novel bed as a whole, the letter B the bed frame; C a mattress supporting means; D means for adjusting the mattress supporting means; and E means for rendering the means D inoperative.

30 The bed frame B may include a conventional head board 10, foot board 11, a pair of side rails 12 connecting the head and foot boards 10 and 11, and there may be provided preferably two pairs of horizontally-disposed stubs or members 13 and 14 extending inwardly from the side rails 12 at spaced apart intervals between the head and foot boards 10 and 11, the stubs 13 facing each other and the stubs 14 also facing each other.

35 A mattress supporting means C is provided and preferably comprises a fixed section 15, a first movable or pivoted section 16 and a second movable or pivoted section 17, spaced inwardly of the vertical planes of the side rails 12, as in Figure 2.

40 The fixed section 15 may be supported in any approved way to the side rails 12, as by brackets 18 and the section 15 includes side bars or members 19 having tongues 20 at their ends. Suitable supporting wires 21 may extend from one bar 19 to the opposite bar 19. The fixed section 15 is disposed intermediate the head and foot

boards 10 and 11 and, in the example shown, is substantially midway these boards.

At the head board end of the means C is the first movable section 16. It is provided with side bars or members 22, which may be similar to the bars 19 and an end bar or member 23 joining the side bars 22 at the head board end of the section 16. Preferably, a rigid stub or member 24 extends inwardly from each of the side bars 22 intermediate the ends of the side bars. At their free ends, the side bars 22 are slotted, as at 25 to accommodate the tongues 20, so that suitable pivot pins may connect the sections 15 and 16. Supporting wires 26 may extend from one side bar 22 to the other and be disposed above the rigid stubs 24. Pivoted as shown and described, the first movable section may assume various inclined planes. If desired, a pair of bumpers 21 may extend outwardly and downwardly from the side bars 22 to the side rails 12.

The second movable section 17 is disposed at the foot board end of the means C and is, preferably, in two portions 28 and 29, these portions being pivoted together, at the ends of their respective side bars or members 30 and 31, in the tongue, slot and pivot pin manner of pivotally connecting the first movable section 16 to the fixed section 15, and the portion 28, being nearest the fixed section 15 is pivotally connected thereto in the same tongue, slot and pivot pin manner. The side bars 31 of the portion 29 are joined together by an end bar 32. Depending from the side bar 31 may be a pair of conventional rollers 34 contacting the uppermost faces of the side rails 12. Supporting wires 35 may extend from one side bar 30 to the other and from one side bar 31 to the other as well as from one side bar 30 to the other side bar 31 as in Figure 2, where it will also be noticed that, in places, the various supporting wires 21, 26 and 35 overlap. Depending from each of the side bars 30 is a pair of spaced-apart perforated ears 36, and from each of the side bars 31, a pair of spaced-apart perforated ears 37, these pairs of ears being nearest the pivotal connection of the portions 28 and 29, all for a purpose later to be described.

Means D for adjusting the mattress supporting means C so that the movable sections 16 and 17, as well as the portions 28 and 29 may be moved to assume various inclined positions as well as to lay flat, includes, preferably, a pair of cylinders 40, for the movable section 16, pivotally connected to the bed frame B at adjacent the side rails 12, as by hangers 41 pivotally carried by the stubs 13. Normally, these cylinders are inclined from the vertical, with their lower ends nearest the head board 10. Each cylinder 40 is provided with a piston 42 and a piston rod 43 extending from a piston 42, upwardly thru a cylinder 40 to the rigid stub 24, where it is preferably pivotally connected thereto as, for example, as shown in Figure 9, where a conventional split coupling is shown, of two portions 44 and 45 each having a semi-circular depression 46, adapted to loosely embrace the bar 24, secured together as by bolts 47 and nuts 48.

Suitable supported from the bed frame B is a plate 54. The support for this plate 54 may be a removable clamp portion and associated bracket portion 55, shown particularly in Figure 8, where a split clamp portion 56 embrace a side rail 12 and the bracket portion 57 extends upwardly as at 58 and outwardly as at 59 and is attached to the under side of the plate 54 as by 75

screws 60 as in Figures 8 and 2. Since there are similar arcuate rows of screw threaded sockets 61 adjacent each side edge of the plate 54, the support for the plate 54 may be attached thereto at either side, whereby the plate may be positioned at either side of the bed.

This plate 54 is preferably flat and horizontally disposed and provided with a perforation 62, shown in Figure 3, and four screw threaded perforations 63, as the example in Figure 7, for a purpose to be described. It will be noted in Figure 2 that the plate 54 is wholly outside the vertical planes of the bed frame B and means C. While its main function is to support portions of the means D to be described, it may be employed as a table top to advantage. Extending upwardly from the plate 54 is a pivot means 64 for a pump handle to be subsequently described.

Secured to its in any approved way, as by the screw 65, and depending from the bottom of the plate 54 is a tank or reservoir 66, for fluid 67, disposed intermediate the ends of the plate. From this reservoir extends a pipe 68 leading to the bottom portion of a pump cylinder or housing 69 with a suitable check valve 70 adapted to admit fluid 67 to the pump housing 69 from the tank 66 but prevent its return thereto thru the pipe 68. The pump mechanism may include a pump piston 71, and a pump rod 72 secured thereto at one end and with its other end extending upwardly thru the perforation 62 in the plate 54, for reciprocation therethrough.

A suitable, preferably removable, pump handle 73 is provided, pivoted at one end to the pivot means 64, extending thru an eye 74 in the upper end of the rod 72 and disposed normally substantially horizontally and projecting toward the head of the bed, so as to be within reach of an invalid or other person in the bed A.

The pivoted end of the pump handle 73 may be inwardly curved as at 75, and provided with a springy metal snap 76 secured to the end of the curve, providing, in effect, a snap hook extending thru an eye 77 in the means 64, so that the handle may be slid toward the foot of the bed and readily removed, whereupon it would be very difficult to operate the pump.

Pivots secured to each pair of depending ears 36 of the side bars 30, is a cylinder 78, shown particularly in Figure 13, having a piston 79 and piston rod 80 extending through the cylinder 78 and pivotally connected at its free end to and between one pair of the ears 37 of the side bars 31. So disposed, the two cylinders 78 lie mainly underneath portions of the side bars 30 and 31 and are adapted to operate to provide the adjustments shown in Figures 4 and 5, as well as many other adjustments, of the portions 28 and 29, when the movable section 17 is raised with the rollers 34 out of contact with the side rails 12. At the base of each cylinder 78 is a conventional nipple 81 leading to the chamber 82 within the cylinder.

From the bottom of the pump housing 69 extends a suitable perforation surrounded by a pipe coupling for a conduit section 83 which may extend under the tank 66 and then upwardly to a valve block 85 to be described. A suitable check valve 84 may be provided at the pump end of the conduit section 83 to prevent return flow of fluid to the pump, as shown in Figure 12.

The valve block 85 shown particularly in Figures 6 and 7, may be made up of two sections, an upper section 86 and lower section 87, together having suitable spaced-apart recesses for five

valves, and suitable conduits from and to certain of the valve recesses and valves. The block sections may be joined together by suitable screws 88 and secured to the side of the tank as by an encircling clamp ring 89, extending around the tank 66 and one end of the valve block 87, having a pair of outwardly extending perforated ears 89a, as in Figures 8 and 10 through which extend a bolt 90 having a nut 91 for tightening and loosening the clamp ring 89, as is well known. A suitable gasket may be disposed between the valve block 85 and tank 66, in order to exclude fluid from leaking out.

More specifically, there is provided in the block sections 86 and 87 a horizontally-disposed valve recess and valve 92 which controls the passage of fluid 67 from the pump to valves 93, 94 and 95. There is a suitable horizontally-disposed recess and a three-way valve 93 therein to control the passage of fluid 67 from the valve 92 to the cylinders 40, a suitable horizontally-disposed recess and a three-way valve 94 to control passage of fluid 67 from the valve 92 to the cylinders 50, and a horizontally-disposed recess and a three-way valve 95 to control the passage of fluid 67 from the valve 92 to the cylinders 78.

From an end of the conduit section 83 which end is coupled to the bottom of the valve block 85 in any approved way, extends a conduit section 96 to one side of the valve 92; from a position 45° from where the conduit section 96 opens into the valve 92, extends a conduit section 97 to one side of the valve 93, from substantially 45° around the valve 93 from this conduit section 97 extends a conduit section 98 to the exterior of the valve block and to a suitable nipple 99 secured to the block. From a position substantially 150° around the valve 92 from the conduit section 96 is a conduit section 100 leading to one side of the valve 94; from a position substantially 90° around the valve 94 from the conduit section 100 is a conduit section 101 leading to the exterior valve block and terminating in a nipple 102; and from a position substantially 210° around valve 92 from the conduit section 96 is a conduit section 103 leading to one side of the valve 95. It will be noted in Figure 6 that there is also an arcuate opening 104 in the valve 92 of somewhat greater than 90°.

Extending from a position around the valve 95 from a location about 90° from the conduit 103 is an L-shaped conduit 104 leading to the bottom of the valve block 85 and to a conventional nipple 104" extending from the bottom.

Extending from the nipple 99 is a conduit section 105 provided with two branches 106 and 107 to each of the cylinders 40, from the nipple 102 extends a conduit section 108 having two branches 109 and 110 to cylinders 50 and from the nipple 104 extends a conduit section 111 having two branches 112 and 113 leading to the cylinders 78. From the arrangement described and illustrated in Figures 2 and 3, it is apparent that fluid 67 may be controlled to flow to and from either the cylinders 50 to elevate or lower the movable section 17, to the cylinders 40 to elevate or lower the movable section 16, to the cylinders 78 to adjust them as desired or may flow to elevate and lower both sections 16 and 17 as well as hold the portions 28 and 29 of the section 17 rigid, all at the same time. Of course, with a proper valve manipulation, the cylinders 78 may be operated independently of the other cylinders. Preferably suitable valve stems for control of the valves 92, 93, 94 and 95 extend upwardly thru the valve 75 16 and 17.

block 85 and plate 54, and terminate in handles 115, 116, 117 and 118. These handles or the upper face of the plate 54 may contain suitable indicia for manipulation of the valves. In order to relieve the system of an excessive fluid pressure, if such excessive pressure might develop a suitable by-pass is provided, which may comprise an L-shaped conduit 120 extending from intermediate the ends of the conduit section 96 to the interior of the tank 66. Interposed in this conduit 120 is a suitable pressure valve, shown as a spring-urged ball valve 121.

In order to prevent lowering of the movable sections 16 and 17 even when the valve handles 115, 116 and 117 are manipulated (of course raising of the sections 16 and 17 is prevented by removal of the handle 73) a valve assembly is provided, with its stem and handle, remote from the head of the bed and beneath the plate 54, substantially out of reach of the occupant of the bed. This valve 125 is contained in a suitable recess in the valve block 85 and is a four-way valve, shown in Figures 6 and 7, and is disposed upon a vertical axis so that its stem extends horizontally, thru the side of the block and terminates in a suitable handle 126 which is inwardly of the vertical planes of the edges of the plate 54. From one side of the valve 125 extends a conduit section 127 to the side of the block adjoining the tank 66 where a perforation in the gasket between the block and tank and a perforation in the tank wall provides a passageway for fluid back to the tank. Substantially 45° around the valve 125 from this conduit section 127 is a conduit section 128 to the valve 93, aligning at the point it reaches the valve 93, with the conduit section 98, substantially 90° around the valve 125 from the conduit section 128 is a conduit section 129 to the valve 94, aligning at the point it reaches the valve 94, with the conduit section 101, and substantially 90° from the conduit sections 127 and 129 is a conduit section 130 to the valve 95, aligning at the point it reaches the valve 95 with the conduit section 104.

From Figure 7 will be seen that an eight turn 45 of valve 125 will close off all conduit sections 128, 129 and 130, while the position of the valve 125 in Figure 7 and positions of valves 93, 94 and 95 as in Figure 6 will permit fluid to slowly drain back into the tank due to the weight of the occupant upon the elevated movable section 16 and/or 17. Of course, some steady pressure of any kind upon the sections 16 and 17 will cause back-flow of fluid, but such back-flow can be prevented by manipulation of valve 125, as explained. Of course, manual adjustment of the degree of angularity of the portions 28 and 29 may be effected when valve 125 is in the position shown in Figure 7.

When the movable section 17 rises it will form various inverted V's in cross section, as shown in Figures 3 and 5 so that an occupant of the bed A may bend his legs.

Since there is no ratchet nor wholly manual operation of raising and lowering the movable sections, but a steady even movement, free of jars or jerks, there is no abrupt movement imparted to the bed occupant's body.

With the pump handle 73 within easy reach of the bed occupant, he may raise the sections as desired, and both manipulation of the handle, as well as the consequent bending of the body, provides slow, even movements to the body, if such exercise is desirable, since the occupant may alternately raise and lower the movable sections

On the other hand, by removal of the pump handle 73 and proper manipulation of the valve 125, the movable sections may be fixed into position against change by the bed occupant, for the valve handle 126 of the valve 125 is both below the plate 54 and faces away from the occupant, being concealed by the intervening pump 69, tank 66 and valve block 85, as well as by the plate 54.

While the degree of angularity of the portions 28 and 29 may be varied, it is possible to make a hydraulic adjustment as shown in Figure 4, which could not be readily effected without the use of the cylinders 78.

Various changes in the shape, size and arrangement of parts may be made, without departing from the spirit of the invention or the scope of the claims.

I claim:

1. In an invalid bed, a bed frame including a head board, a foot board and side rails; a mattress-supporting means, including a fixed section carried by said rails and disposed intermediate the head and foot boards, a first movable section extending from said head board to an end of said fixed section and pivoted at said fixed section, and a second movable section extending from the opposite end of said fixed section to said foot board and pivoted at said fixed section; operating means for swinging said movable sections into various planes above the horizontal planes of said rails, including a substantially horizontally disposed plate supported by one of said side rails in a position outwardly of the vertical planes of said frame, a fluid, a reservoir for said fluid, carried by said plate, a pump for said fluid, operatively connected with said reservoir and carried by said plate, a pump handle pivoted at one end to said plate, operatively connected with said pump, substantially paralleling said rails and extending toward said head board, a cylinder carried by said frame adjacent said first movable section, a cylinder carried by said frame adjacent said second movable section, a piston and a piston rod for each cylinder with the free end of one rod operatively connected with said first movable section, and the free end of the other rod operatively connected with said second movable section, a conduit from said pump to adjacent the bases of said cylinders and a conduit opening into said first conduit and extending to said reservoir, means to direct fluid from said pump selectively to either or both of said cylinders, and releasable means to prevent return of fluid to said reservoir from said cylinders, said means being interposed at the juncture of said conduits and disposed below said plate and at a location remote from the free end of said pump handle.

2. In an invalid bed, a bed frame including a head board, a foot board and side rails; a mattress-supporting means, including a fixed section carried by said rails and disposed intermediate the head and foot boards, a first movable section extending from said head board to an end of said fixed section and pivoted at said fixed section, and a second movable section extending from the opposite end of said fixed section to said foot board and pivoted at said fixed section; operating means for swinging said movable sections into various planes above the horizontal planes of said side rails, including a substantially horizontally disposed plate supported by one of said side rails in a position outwardly of the vertical planes of said frame, a fluid, a reservoir for said fluid, carried by said plate, a pump for said fluid, operatively connected with said reservoir and car-

ried by said plate, a pump handle pivoted at one end to said plate, operatively connected with said pump, substantially paralleling said rails and extending toward said head board, a cylinder carried by said frame adjacent said first movable section, a cylinder carried by said frame adjacent said second movable section, a piston and a piston rod for each cylinder with the free end of one rod operatively connected with said first movable section, and the free end of the other rod operatively connected with said second movable section, a conduit from said pump to adjacent the bases of said cylinders and a conduit opening into said first conduit and extending to said reservoir; valve means to direct fluid from said pump to either or both of said cylinders; and releasable means to prevent return of fluid to said reservoir from said cylinders, said last means being interposed at the juncture of said conduits and disposed at a location remote from the free end of said pump handle.

3. In an invalid bed, a bed frame including a head board, a foot board and side rails; a mattress-supporting means, including a fixed section carried by said rails and disposed intermediate the head and foot boards, a first movable section extending from said head board to an end of said fixed section and pivoted to said fixed section, and a second movable section extending from the opposite end of said fixed section to said foot board and pivoted at said fixed section; operating means for swinging said movable sections into various planes above the horizontal planes of said rails, including a substantially horizontally disposed plate supported by one of said rails in a position outwardly of the vertical planes of said frame, a fluid, a reservoir for said fluid, carried by said plate, a pump for said fluid, operatively connected with said reservoir and carried by said plate, a pump handle pivoted to said plate, operatively connected with said pump, extending toward said head board, a cylinder pivotally carried by said frame adjacent said first movable section, a cylinder pivotally carried by said frame adjacent said second movable section, a piston and a piston rod for each cylinder with the free end of one rod operatively connected with said first movable section, and the free end of the other rod operatively connected with said second movable section, a conduit from said pump to adjacent the bases of said cylinders, a conduit opening into said first conduit and extending to said reservoir, valve means to direct fluid from said pump selectively to either or both of said cylinders, and releasable means to prevent return of fluid to said reservoir from said cylinders, and render said operating means inoperative, said last means being interposed at the juncture of said conduits.
